ELISHA F. BEAVERSTOCK, OF HOLYOKE, MASSACHUSETTS.

WEFT BINDING AND SEVERING DEVICE FOR LOOMS.

1,191,653.

Specification of Letters Patent. Patented July 18, 1916.

Application filed July 8, 1914. Serial No. 849,648.

To all whom it may concern:—

Be it known that I, ELISHA F. BEAVERSTOCK, a citizen of the United States of America, and resident of Holyoke, in the county of Hampden and State of Massachusetts, have invented certain new and useful Improvements in Weft Binding and Severing Devices for Looms, of which the following is a full, clear, and exact description.

10 This invention relates to devices or appliances included in automatic looms of a well known type, in which bobbins, from supplying means therefor, are periodically delivered into the shuttle, causing the expulsion 15 of the shuttle bobbin from which the weft thread is exhausted; and in the above mentioned type of loom there is employed a so-called "feeler," which co-operates with the more or less filled bobbin so that when the 20 thread on the bobbin is substantially exhausted, or so that there is but very little thread remaining on the bobbin, the feeler will cause the rocking of a shaft which actuates the forcing of a fresh filled bobbin from 25 the magazine or bobbin supply into the shuttle simultaneously securing the expulsion from the shuttle of the exhausted bobbin.

The improvements of the general character to which the present invention relates 30 are set forth in an application for Letters Patent of the United States filed by me April 3, 1913, Serial No. 758,598, the same including a device opposite the location of the mouth or inner end of the shuttle box 35 which is operable to both temporarily bind the weft, and also to sever it near where it is bound at the time when the shuttle is to be replenished with a fresh bobbin, holding the end portion of the weft which extends 40 in an outward direction from the selvage; and a second device opposite the location of an intermediate part of the shuttle box which is operable to temporarily bind the portion of the weft between the first binding and cutting device and the point where the weft emerges from the shuttle, the said 45 second device being also operable to cut the weft near the point where it is bound by the second device. These devices are provided for 50 the purpose of preventing the remnants of the weft from an exhausted bobbin becoming entangled with the weft of the fresh bobbin to thereby improperly become woven into the cloth.

55 The companion binding and cutting devices shown and described in my afore-

named application, include as to each a single pair of relatively movable binder jaws or members in conjunction with an adjacently located cutter. Experience in the employment of these devices shows that the binding of the weft by each of the devices at a single point is not reliable, especially with yarns or thread of certain quality and degree of fineness; and the object of the 60 present invention is to so construct the companion binding and cutting devices that each will have means for the acquirement of a plurality of bindings of the weft thread at points comparatively close to each other 65 and all adjacent the point of cutting.

A further object of the invention is to provide means for slight transverse or lateral adjustments of the several jaws comprised in the binding and cutting devices so 75 that each thereof may be set up with a nicety for its best coaction with the part or member with which it works to bind or cut the weft as the case may be.

With these and other objects in view, the 80 invention is described in conjunction with the accompanying drawings and is set forth in the claims.

In the drawings:—Figure 1 is a side elevation of the combined binding and cutting 85 device, the parts thereof being in open position, and as when the device as a whole is withdrawn or retired from proximity to the path of the shuttle and to the lay. Fig. 2 is a view similar to Fig. 1, but showing the parts 90 as in their closed relations as assumed when the device as a whole is swung toward the path of the shuttle and to a position to be actuated by the lay. Fig. 3 is a plan view of Fig. 1. Fig. 4 is a side elevation of parts of 95 the device as seen with some of the conjunctive parts removed. Fig. 5 is a substantially horizontal longitudinal sectional view as taken on line 5—5, Fig. 1. Figs. 6, 7 and 8 are cross sectional views as taken about 100 on the lines 6—6, Fig. 1, and showing the relations of the parts comprised in the "first" binding and cutting device at different times or stages in the operation. Fig. 9 is a side view of the shoe or buffer provided 105 on the face of the extremity of the arm which carries the first binder and cutter.

Lying against the face of the arm G, which arm forms the oscillatory support for the first binder and cutter, is a thin plate $\mathfrak{f}^3$ 110 having a sharp or shear cutting edge. Offset and spaced from this shear $\mathfrak{f}^3$ is a body

G^3 formed with a goose necked extremity G^4 and held immovable in its position of separation from the side of the arm, and the shear, in part by the transverse stud G^5 and in part by being held on the pivot stud g between the binder jaws j and j^2 . This body G^3 , G^4 while ordinarily immovable relatively to the arm G is bodily transversely adjustable within slight limits toward or away from the face of the arm. The said body G^3 is formed bifurcated at its extremity which is toward the free end of the arm, as will be perceived in Fig. 5, whereby there is a vertical opening G^6 between the opposite jaw forming portions G^7 , G^8 , such portions being bifurcated or notched more or less similar to the notching of the arm G .

As practised in construction, the body G^3 is formed of three flat plates facewise arranged and united, the intermediate plate being less long than the plate at opposite sides thereof and serving as a spacing member for the outer plates and for the creation of the aforementioned bifurcation G^6 , the opposite boundaries of which are in vertical planes.

Matched with the body G^3 in the manner of a shears, and at opposite sides thereof are the binder plates j and j^2 united at their heel portion j^3 by a spacing block and rivets, as indicated in Fig. 4, these paired binder jaws rocking on the pivot g as likewise does the cutter jaw j' which lies facewise relatively to the inner binder jaw J^2 and between such jaw and the fixed cutter or shear jaw j^3 .

The movable cutter jaw j' at the heel portion j^3 of the combined parts is united to the binder jaws by the transverse rivets, but from its pivot toward its free or working end, it is unattached to the adjacent binder jaw j^2 .

In the space in the bifurcated extremity of the aforementioned fixed body G^3 also pivotally hung on the pivot stud g is an angular element j^4 , the shape of which is best seen in Fig. 4, and which comprises the finger or jaw j^4 at its lower portion, a cleaver finger j^5 above the crotch between such fingers and an actuation finger j^6 .

When the carrying arm G is swung from its retired position rearwardly of the loom and toward or to the path of the shuttle, with the jaw devices in their open positions as indicated in Figs. 1 and 6, the lay in beating up will bring the spring pressed stud e on the top of the shuttle box against the actuation finger to cause, as shown in Fig. 2 the part j^6 to be swung so as to carry its binder finger j^4 between the jaws G^7 , G^8 , of the fixed body G^3 above the crotch at the extremities of such jaws to obtain a double binding of the weft thread in two places as shown in Fig. 7. This action is almost instantaneously followed by a part or abutment on the lay striking the heel portion j^3 of the

combined movable binder jaws and shear jaw whereby the latter are swung to their closed relations indicated in Figs. 2 and 8 securing two additional bindings of the weft thread below the crotch in the jaws, and then thereafter the cutting of the thread near where it has the plurality of bindings.

The jaws are thrown into their open position after the arm has retired forwardly or outwardly following the bobbin replenishment,—carrying the thread held thereby outwardly away from the path of the shuttle and only to release the thread after it shall have been carried to such out of the way position, by having the stud i carried by the uniting heel j^3 of the binder jaws engage a trip member i^2 represented in dotted lines in Fig. 1 and which is mounted on any suitable support and in any suitable position relative to the path of movement of the stud i and incapable of yielding in an upward direction but capable of yielding downwardly so that upon the backward swing of the arm G the stud may ride over the trip member i^2 to occupy its position slightly beyond it and for coaction therewith on the next inward swing of the arm, to cause the movable combined jaws to open. The mode of and means for the causing of the combined movable jaws to seasonably have their opening and closing movements are the same as heretofore usually practised and utilized in respect of the cutter jaw and single binder jaw in automatic looms.

As the angular device j^4 is swung downwardly to its normal or non-binding position, represented in Fig. 4, the clearer finger j^5 receding in the downward direction to occupy a position about where the binder finger j^4 had previously been, positively ejects the looped portion of the thread from between the jaws G^7 , G^8 , above the crotch in the extremity thereof.

The bolt g is screw threaded and adjustable transversely relatively to the arm G and it has a pair of shoulders g^9 and g^{10} closely together on the intermediate part thereof in engagement at either side of the normally fixed cutter jaw j^3 , the shank portion of which by the screw g^{10} is secured on the side of the arm at quite a distance from the pivot. These shoulders may be made as collars screw threaded or otherwise engaged in their adjacent positions on the pivot stud, g .

By loosening the nut g^9 and turning the pivot stud, such stud may be axially adjusted to carry the extremity of the cutter jaw j^3 which extremity is unattached relatively to the arm slightly away from such arm to bring it to position for its best shearing coaction with the movable cutter jaw j' .

In order to impart to the movable jaws a slight degree of obliqueness, they severally have perforations through an upper portion thereof through which a bolt e traverses, the

same having a head c' at one end and receiving at its opposite threaded end an adjusting nut c^4 and a lock nut c^4 , there being interposed in the spacing between the jaws a spiral spring c^5 which is in compression, and encircles the intermediate portion of the bolt.

By loosening the nuts the upper portions of the jaws will, by the spring c^5 , be subject to a separating force so that they are slightly tilted on the pivot stud g so as to be oblique to the true vertical planes, thereby insuring that the movable binder jaws will have their best binding coaction with the fixed jaws G^7 of the normally stationary body member G^8 .

Extending outwardly beyond the face of the outer binder jaw j is the threaded extremity of the pivot stud g which has thereon a spring, or resilient washer g^6 and a single, or duplicated binding nuts g^4 , which provision is efficient for holding the binder jaws in the adjustments which may be imparted thereto independently of the adjustment which is imparted to the cutter jaws.

Inasmuch as transverse adjustments of the cutter jaw j^2 by the axial movement of the pivot g tend to cause corresponding transverse displacement and possible distortion of the aforementioned body G^3 , provision is made for a second adjustment of such body at the goose neck portion or shank G^4 thereof, the same being seen to consist in the transverse bolt or stud G^8 , the headed end of which is in engagement with the parts G^9 while it receives locking nuts G^9 and G^{10} on the portion thereof which is threaded through the arm G ,—see Fig. 5.

When the threaded stud G^8 is turned to permit the body G^3 to move away from the side of the arm G , the spring G^{12} between the part G^4 and arm, operates to positively effect such movement, thereby facilitating in the operation of adjustment and preventing an undue tilting to an oblique position of the shank or goose neck portion of the body G^3 .

The body member in which the fixed binder jaws G^7 are comprised, has to the rear of the pivot g a longitudinal slot v^2 therethrough and the opposite movable binder jaws have a slot v^4 with a curved wall.

A floating stud v^3 is provided to extend through all the said slots,—its ends thereof not projecting outwardly beyond the faces of the movable binder jaws or plates and it is held against displacement by the cap plate v^5 .

The spring v in the longitudinal slot v^2 presses the floating stud against the curved edges of the slots v^4 ; and this provision is operative to maintain the movable combined jaws in the positions to which they may be brought in the operation of the device, either opened or closed, without liability of their becoming accidentally, or from any cause,

closed while they should remain open, or vice versa.

On the side of the arm G opposite to that at which the cutter and binder jaws are located, is a shoe T of iron or other suitable material penetrated by the studs or bolts g and G^8 and retained by the nuts as shown in Fig. 5. This shoe is made with a thickened extremity T^2 having a recess T^3 at its extremity and opening to its end, the opposite walls of which are beveled as shown in Figs. 6, 7, 8 and 9. This shoe being on the side of the arm which is faced toward the end of the shuttle box is a provision to prevent the steel ended shuttle after coming into the box and rebounding, from striking against and gouging or mutilating the arm. It also serves to maintain the shuttle at its proper working line, preventing the same from having any rising movement in the shuttle box.

In the operation of the loom the shuttle shoots across the lay into the shuttle box as the lay is swinging for its beat-up, passing the end of the arm before the lay is fully up to such a position that the path of the shuttle would intersect the extremity of the inwardly presented arm; but the timing action of the parts is such that between the time the shuttle has passed the location of the arm and reached and brought up against the picker stick, and the lay is fully to its beating up position on the rebound the steel pointed shuttle frequently has an impact against the extremity of the arm which, although of metal, soon becomes badly gouged or mutilated, and necessarily must be replaced; but the presence of the non-metallic shoe in the situation stated prevents injurious effect to the arm and in course of time, as may be required, a new shoe may replace the one formerly used at small expense and without the necessity of discarding the arm, and the parts carried thereby.

I claim:

1. In a device of the character described, a supporting and carrying member having a normally fixed cutter jaw and binders comprising a normally fixed binder member and movable binder jaws at opposite sides of such binder member and a cutter jaw associated with one of the movable binder jaws for coaction with the normally fixed cutter jaw,—said double binder jaws and the movable cutter jaw being pivotally mounted for coaction respectively with the fixed binder member and the normally fixed cutter jaw.

2. In a weft binding and severing device of the character described, a supporting and carrying member having a normally fixed cutter jaw, and binders comprising a normally fixed binder member, having a vertical, forwardly opening recess within its

- thickness and extending vertically there-through and movable binder jaws at opposite sides of such binder member and a cutter jaw associated with one of the movable binder jaws for coaction with the normally fixed cutter jaw,—said double binder jaws and the movable cutter jaw being pivotally mounted for coaction respectively with the fixed binder member and the normally fixed cutter jaw, and a member pivotally hung in the said recess of the normally fixed binder member, and operative when swung to secure two bindings of the thread additional to those between said movable and fixed binder jaws; and means for imparting a swinging motion to the pivotally hung member.
3. In a weft binding and severing device of the character described, a supporting and carrying member having a normally fixed cutter jaw, and binders comprising a normally fixed binder member, having a vertical, forwardly opening recess within its thickness and extending vertically there-through and movable binder jaws at opposite sides of such binder member and a cutter jaw associated with one of the movable binder jaws for coaction with the normally fixed cutter jaw,—said double binder jaws and the movable cutter jaw being pivotally mounted for coaction respectively with the fixed binder member and the normally fixed cutter jaw, and a member formed with a forwardly opening recess pivotally hung to the said recess of the normally fixed binder member, and operative when upwardly swung to secure by its portion below the recess therein two bindings of the thread additional to those between said movable and fixed binder jaws, and to secure on its downwardly swung movement by its portion below the recess therein a clearing of the previously bound thread, and means for imparting a swinging motion to the pivotally hung member.
4. The combination with the supporting and carrying member of a normally fixed cutter jaw, the shank portion of which is secured on the side of the supporting member while its extremity is transversely deflectable relatively to the latter, a pivotally mounted cutter jaw for coaction with the normally fixed cutter jaw, a pair of spaced pivotally mounted binder jaws and a fixed member between and with which the latter jaws coact, means for transversely adjusting the deflective extremity of the normally fixed cutter jaw without disturbing the relation of the coacting binder members.
5. In a device of the character described, the combination with a supporting and carrying member, of a normally fixed cutter jaw, the shank portion of which is secured on the side of the supporting member while its extremity is transversely deflectable relatively to the latter, a pivotally mounted cutter jaw for coaction with the normally fixed cutter jaw,—said double binder jaws and the movable cutter jaw being pivotally mounted for coaction respectively with the fixed binder member and the normally fixed cutter jaw, and a member pivotally hung in the said recess of the normally fixed binder member, and operative when swung to secure two bindings of the thread additional to those between said movable and fixed binder jaws; and means for imparting a swinging motion to the pivotally hung member.
6. The combination with a supporting and carrying member of coacting fixed and movable cutter jaws and coacting fixed and movable binder jaws and means for adjusting the binder jaws bodily relatively to the cutter jaws without varying their relations and independent means for varying the relations of the binder jaws.
7. The combination with a supporting and carrying member, of a normally fixed cutter jaw, the shank portion of which is secured on the side of the supporting member while its forward extremity is transversely deflectable relatively to said supporting member, a pivotally mounted cutter for coaction with the first named cutter jaw, a pair of spaced binder jaws and a fixed member between and with which the latter jaws coact, a stud mounted on the carrying and supporting member on which said pivotally mounted cutter and binder jaws are hung penetrating said fixed member and said stud having shoulders in engagement at opposite sides of the deflectable portion of the normally fixed cutter jaw, and means for adjusting said pivot stud in the line of its axis.
8. In the binder device the intermediate body member and pivotal binder jaws at opposite sides of said member, means coacting with the separated binder jaws for causing tilting thereof to planes oblique to their general parallel vertical planes, and adjustable confining means coacting with said binder jaws adjacent the pivot therefor.
9. In a binding device of the character described, an intermediate body member and pivotal binder jaws at opposite sides of said body member having upper edge portions thereof above said body member provided with transverse perforations, a transverse stud having a head at one end engaging one of said jaws and a nut on the other end of the said stud engaging the other jaw, a spring exerting a separating force between said jaws, and a stud on which said jaws are pivoted extending through the body member and having outside of one of the jaws thereon a surrounding spring washer and a nut screw engaging the stud and adapted to variably tension said washer.
10. The combination with the supporting and carrying member and the normally

- fixed cutter jaw, of a body member spaced from the side of the supporting member and cutter jaw, a pivot stud carried by and transversely extending from the supporting member and extending through and beyond said spaced body member, a combined cutter jaw and pair of binder jaws pivotally mounted on said stud and the binder jaws having a straddling relation to the extremity or jaw 5 portion of the body member, means operative to transversely deflect the extremity of the normally fixed cutter jaw and to correspondingly transversely displace, bodily, the combined movable cutter jaw and double 10 binder jaw and the portion of the body member adjacent the pivot, a stud having a screw 40 thread engagement through the supporting member with a head in engagement with the body member, a set nut for locking this stud relatively to the supporting member, and a spring between the supporting member 45 and the body member for exerting an outward crowding force to the latter.
12. In a device of the character described, the supporting and carrying arm provided with a pivot member and having a normally 50 fixed cutter member, combined cutter and binder members pivotally mounted for rocking movement on said stud,—the body member having the longitudinal slot therein and one or more of the pivotal members having 55 slots with a curved edge, a stud in engagement through both slots, and a spring for forcing said stud against the curved edges of the curved edged slots.
13. In a weft binding and severing device 60 of the character described, a carrying arm having at its one side, normally fixed, and movable, jaw members operable to bind and cut the thread of an exhausted bobbin, and a shoe removably affixed on the other side 65 of the carrying arm, provided with a recess opening to the outer end thereof, the lateral walls of which are outwardly divergent.
